WAVE RECORDING AND REPRODUCTION

Jackson O. Kleber, Long Island City, N. Y., and Lincoln Thompson, Stamford, Conn., assignors to The Sound Scriber Corporation, Stamford, Conn., a corporation of Connecticut

Application June 12, 1939, Serial No. 278,672

12 Claims. (Cl. 179—100.4)

This invention relates to wave transmission methods and means, particularly as applied to the recording and reproduction of sound waves or other waves in low speed record tracks.

In order to compress as much record as possible into a given length of record track, when making a record of sound or other waves, it is desirable to make the recording stylus or other recording device trace the track at a relatively low speed. For example, when a sound record disk rotates at the commercial speed of 33 $\frac{1}{3}$ revolutions per minute, more than twice as much record can be included in a given length of groove as at the commercial speed of 78 revolutions per minute.

Difficulties arise, however, when the linear speed of the record track is low. In the case of a disk record, the track speed is proportional to the radius of curvature of the track, and the speed of the track is so much lower at its inner end than at its outer end that the record is excessively compressed and suffers serious attenuation or loss of the higher frequency components in the reproduced waves at the disk speed of 33 $\frac{1}{3}$ revolutions per minute. The wave lengths of the components of a complex wave recorded in the track, become progressively shorter as the frequencies of the components increase, until at the higher frequencies and the lower track speeds, the reproducing stylus appears to be unable to follow faithfully the fine structure of the recorded waves representing the components of higher frequency, and the reproduced waves are correspondingly distorted or incomplete.

Further difficulties are encountered, if an attempt be made to increase the amplification of the recording current to avoid loss of the higher frequency components. The lower frequency components in this case are recorded and reproduced in such excessively large amplitudes, while the higher frequency components are, in general, reproduced in such small amplitudes at the low track speeds, that the higher frequency components are seriously masked or completely obliterated by the more powerful lower frequency components.

Owing to the relatively short wave lengths of the higher frequency components in the record track at low track speeds, the peaks of these components tend to block the passage of the reproducing stylus along the groove and tend to squeeze the stylus out of the groove as the amplitudes of the higher frequency components increase. In this way the reproducing stylus may be forced to jump completely out of the groove. In some cases the jump may be so violent that

the stylus does not return to the same turn of the groove. Squeezing of the reproducing stylus tends to distort, interrupt and otherwise mutilate the reproduction of the desired waves.

Similar difficulties may be experienced at various low speeds of rotation of the disk type of record, and also with other types of records operating at relatively low track speeds.

An object of the present invention is to provide simple and convenient methods of and means for transmitting waves so that the waves are adapted for recording and reproduction in more intelligible and useful form and so that one or more of the above mentioned difficulties may be reduced or avoided.

Another object is to compactly record waves, for example sound waves, in such a manner that the waves reproducible from the resulting record exhibit less objectionable distortion, loss of identity, or mutilation when compared with the original waves, than would occur when employing the usual methods of recording at corresponding track speeds.

Another object is to apply the methods and means, referred to above, to records of the disk type.

Another object is to provide a recording circuit and a reproducing circuit adapted selectively to transmit waves without incurring shock excitation difficulties.

Other objects are to provide simple and efficient methods of and means for varying the recording characteristics of a wave recording system automatically with change of track speed; to provide a simple and efficient amplifying system in which the characteristics of the amplifier may be varied readily, either at the amplifier or at a place remote from the amplifier; and generally to improve the transmission and other characteristics of wave recording and reproducing systems utilizing relatively low track speeds or utilizing wave lengths in the record track which are short as compared with the dimension of the reproducing stylus or other reproducing pick up measured in the direction of the groove at the place being traced.

In accordance with one aspect of the present invention, sound waves or other waves to be recorded, are given a preliminary compensation or distortion in a predetermined manner during transmission through a section of the wave path between the source of waves and the recorder, so that certain of the waves or components of different frequency are transmitted to the recorder with relative amplitudes differing from

their original relation and so that the waves are recorded in a form adapted for reproduction as a more faithful, more intelligible, or otherwise more useful copy of the original waves.

When the invention is employed for recording on disk records, the waves may be compensated or distorted in portions of the track of smaller radii or of lower track speed, by recording the higher frequency components with a greater amplitude in proportion to that of the lower frequency components than occurs in the waves from the original source, while the waves are recorded in portions of the track of larger radii or higher track speed, either with less compensation or without any compensation. The band of higher frequency components being recorded at the greater amplitude, is preferably increased in width with decrease of track speed, or conversely, the band width is decreased with increase of track speed by changing the transmission characteristic of the wave path. In order to control the relative amplitudes of components of the waves being recorded and the width of the band having increased amplitude, one or more cams may be provided to vary the transmission characteristic of the path in predetermined relation to the recording mechanism, to automatically and progressively change the amount of compensation in the recorded wave with change of track speed, thus varying the transmission of the recording current with frequency according to a predetermined family of curves. By substituting for one cam, another of different contour, a change may be made from one to another predetermined set of curves, so that various different characteristics may be obtained in the reproduced waves without requiring replacement of the impedance elements. A similar cam arrangement may be employed for varying the relative amplitudes of components of the waves reproduced from a record with changes of track speed.

The band of higher frequency wave components recorded with increased amplitude, is preferably limited to a predetermined upper level or maximum gain, thus minimizing objectionable squeeze of the reproducing stylus. When the track speed becomes so low that the compensated higher frequency components of larger amplitude tend to produce a record which might objectionably squeeze the reproducing stylus, as referred to above, the cam is preferably provided with such a contour as to reduce the amplitude of the higher frequency components at the low track speed to minimize objectionable squeeze, while maintaining the amplitude large enough to insure more intelligible reproduction than in the case where the different frequency components are recorded with the same amplitude relation as in the original waves.

In a convenient form of the invention, an amplifier is provided with a negative feed back, having a selective circuit so combined therewith that the resulting amplification, in terms of the ratio of output to input of the amplifier, may be made greater for the components of one frequency than for those of another frequency. The negative feed back circuit includes a coupling circuit between the output and input circuits. A selective circuit is so associated with this feed back circuit as to selectively reduce the negative feed back effect for components of a certain frequency or frequencies, thus causing an increased amplification thereof. The selective circuit thus serves as a selective neutralizer for the negative feed back coupling for selectively uncoupling the feed back and thus

distorting the waves transmitted through the feed back and the amplifier. By employing reactance of only one sign in the selective circuit, shock excitation difficulties may be avoided. The need of a volume control for the uncompensated components is also avoided, and more flexible, efficient and convenient control and operation of the amplifier is possible than when ordinary selective networks outside of the amplifier are employed to control the selective transmission of the current.

These and other objects and features of the invention will be understood more clearly from the following detailed description in connection with the accompanying drawings and the appended claims.

In the drawings,

Fig. 1 is a schematic diagram of one form of circuit illustrative of the invention.

Fig. 2 shows curves representing decibels of gain for current reproduced at different track speeds from a record without high frequency compensation.

Figs. 3 and 4 show curves representing decibels of gain for compensated recording current with different adjustments of the compensation circuit of Fig. 1 or 7.

Fig. 5 shows a different form of compensating circuit for substitution in Fig. 1 or 7.

Fig. 6 shows curves obtainable with the Fig. 5 circuit.

Fig. 7 is a schematic diagram of a push-pull amplifier circuit adapted for substitution in Fig. 1.

Fig. 8 is a schematic diagram of a reproducing circuit.

Fig. 9 shows a curve representing decibels of gain in the compensated amplifier of Fig. 8.

Fig. 10 is a schematic diagram of a wave transmission circuit adapted for substitution in Fig. 1, and having a selective shunt across the line to compensate the recording current.

Referring to Fig. 1, the microphone or other source of waves 1 to be recorded, is coupled with the pre-amplifier 2, labelled A₁, coupled in turn with the transmission control amplifier 3, A₂, coupled with the power amplifier 4, A₃, coupled with the recording head 5, RH, having the recording stylus 6. The recording head 5 is shown as being of the usual inductive impedance type, but may be of any other suitable type. An indicator 35 is connected in parallel with the recording head 5 to show the amplitude of the waves being recorded.

The constant speed motor 7, M, rotates the feed screw 8 to feed the recording head toward the center of the record disk blank, 10, or in a reverse direction by reversing the rotation of the feed screw 8. The disk 10 is supported on the usual turn table 11, having the constant speed drive shaft 9 for rotating the disk in a clockwise direction.

The amplifier 3 has the input transformer coupling or impedance 12 and the output transformer coupling or impedance 13. The input circuit 14 of the amplifier, connected from the cathode 15 to the control element or grid 16, includes in series in the order named, the resistance 17, the negative feed back coupling resistance 18, and the secondary coil of the input transformer 12. The output circuit 19, connected from the cathode 15 to the anode 20, includes in series in the order named, the resistance 17, the source of current 21 for positively polarizing anode 20, and the primary coil of the output transformer 13.

The desired amount of negative polarizing potential for grid 16 to insure of linear amplification, is obtained by adjusting resistance 17. The capacity 22 shunting the resistance 17, bypasses alternating current components around the resistance.

The variable resistance 23 in series with the low impedance blocking condenser 24, is connected from the output circuit 19 at the anode 20, to the input circuit 14 at the terminal of resistance 18 remote from resistance 17. The selective compensating circuit 25, shunted around coupling resistance 18, includes impedance elements consisting of the variable capacity condenser 26 in series with the variable resistance 27.

One end of the rack bar 28 is attached to the recording head 5, the other end being slidably longitudinally through the fixed guide 29, while the head 5 is fed across the disk 10. Rack teeth 30 along one edge of bar 28, mesh with one or more pinions 31, 31, etc., fast to one or more shafts 32, 32, etc., free to rotate in and supported by the stationary frame 33. One or more cams 34, 34, etc., removably supported on shafts 32, 32, etc., respectively, may be locked thereto by hand screws 36, 36, etc. One or more cam-following plungers 37, 37, etc., are free to slide longitudinally while guided by the frame 33, the plungers being pressed endwise into contact with the cams 34 by the springs 38, 38, etc., compressed at one end by the frame 33 and at the other end by the collars 39, 39, etc., fastened to the plungers 37.

Rack teeth 40 along the edge of each plunger, mesh with a pinion 41, fast to each shaft 42, journaled in frame 33. Rotation of one shaft 42, varies the capacity of condenser 26, and rotation of another shaft 42, varies resistance 27.

When the recording head 5 feeds toward the center of disk 10, the rack bar 28 causes the rotation of pinions 31 and cams 34 in a clockwise direction, thereby controlling the longitudinal position of plungers 37, which in turn control the rotational positions of pinions 41 and shafts 42, and the corresponding adjustments of condenser 26 and resistance 27, so that the compensation circuit 25 automatically may be given a desired predetermined adjustment by cams 34, at each part of the record track to correspond with the linear speed of the track, the adjustment of circuit 25 being synchronized with the movement of the recording head 5. Condenser 26, resistance 27, or any other unit, when there are added units as referred to hereinafter, may be varied, or may be held at a fixed value by a cam 34 having a circular contour of suitable diameter.

The usual recording conditions of ordinary recorders may be simulated, if the amplifiers A₁, A₂, A₃, operate as ordinary amplifiers without special provision for frequency selectivity. This result may be obtained with the Fig. 1 circuit, if resistance 18 be first adjusted to a very low or zero value, while resistance 23 is made so high as to act as an open circuit, the amplifier A₂ performing as an ordinary amplifier without feed back, and the cam control mechanism consequently being ineffective to produce any control over the recording current. Assuming sound or other waves within the usual recording frequency range, originating at constant amplitude at the source 1, are transmitted to amplifiers A₁, A₂, A₃, and the recording head 5, the resulting record track when played back in a reproducing operation, reproduces waves with a gain shown by the curves T, V, X, Fig. 2, corresponding, respectively, with the maximum track radius or speed range T, the in-

termidate range V, and the minimum range X, Fig. 1.

While the ideal reproduction characteristic for most purposes might be a horizontal line throughout the utilized frequency range, it will be seen that the actual reproduced waves suffer from serious attenuation or complete loss of the higher frequency components at the low track speeds. The loss of waves shown by the curve X, Fig. 2, is so serious in the case of a speech record, for example, that there may be an almost complete loss of intelligibility, thus making it necessary when intelligibility is desired, to uneconomically limit the recording area, when recording by the old method, to an area of the disk having a relatively large radius.

In order to improve the reproduction of higher frequency waves in accordance with the present invention, the resistance 23 is first adjusted to permit appreciable current to pass from the output circuit 19 to the input circuit 14, the coupling resistance 18 being made large enough in relation to resistance 23 to provide an efficient negative feed back action, while resistance 27 is first made so high that compensation circuit 25 exerts no appreciable effect on the feed back. The compensation circuit 25 may then be adjusted to any desired value to selectively shunt the resistance coupling 18 and thereby to give the amplifier 3 a frequency selective characteristic or in other words a predetermined distortion characteristic having the desired compensating effect. It will be seen that circuit 25, by virtue of its shunting action, is adapted to selectively neutralize or uncouple the negative feed back coupling 18, thereby causing a selective increase in amplification.

The impedance characteristic of the condenser 26 in series with the resistance 27, as an uncoupling circuit, has been found to be especially effective and convenient for a wide range of adjustments of the transmission level of the components of different frequency to be recorded. One advantage is that the use of a selective circuit having only one kind of reactance therein, makes it possible to avoid shock excitation effects, thus improving the quality and intelligibility of the reproduced waves. Another important advantage is that the impedance of circuit 25 at any given setting can be made to decrease smoothly as the frequency increases, so that the resulting amplification increases smoothly for the higher frequencies to be recorded.

A further advantage is that the low frequency components which need no increased amplification for the low track speeds, remain unaffected by the compensation circuit 25. The need for an extra volume control for the amplifier is thus avoided. A still further advantage with this form of circuit, is that the point on the frequency scale where waves of increasing frequency begin to receive an increase of amplification, may be readily adjusted up or down scale by merely adjusting the value of condenser 26 or resistance 27. The slope of the curve of increasing amplification may be conveniently adjusted within wide limits by adjusting resistance 27. Since no inductance is needed in this form of compensation circuit, the problem of stray magnetic fields and magnetic shielding is avoided. The type of amplifier shown in Fig. 1 is particularly adapted to have its compensation control circuit 25 placed at a distance from the other parts of the amplifier circuit for convenient remote control.

Cams 34, 34, are given such contours that they

progressively and smoothly adjust condenser 26, or resistance 27, or both, to provide the desired selective amplification at the various track speeds.

In many cases it is preferable to simplify the circuit 25 and its control by adjusting resistance 27 to a fixed small or zero value throughout the recording operation; adjustment of the capacity of condenser 26 alone being relied upon for obtaining the desired compensation for the higher frequency components in the recorded wave.

Fig. 3 shows a typical family of curves representing the decibels of gain of amplifier 3, plotted against frequency for different adjustments of condenser 26 when resistance 27 is zero. The utilized frequency range may extend, for example, from 50 cycles to 10,000 cycles per second, but may be more than this, or may be considerably less.

Curve T shows the gain with condenser 26 at its zero value wherein the compensation circuit 25 is open, as in Fig. 1, so that the negative feed back action is at a substantially constant maximum value throughout the utilized frequency range, thus providing substantially distortionless transmission of the waves through the amplifier, the amplification being at a relatively low value. Curves U, V, W, X, show the gain, respectively, when using the four successive values of the capacity of condenser 26, obtained when the shaft 42, Fig. 1, rotates in a clockwise direction to connect, first, one condenser in circuit, then two in parallel, then three, and finally four condensers 26 in parallel, shunting the negative feed back coupling resistance 18. Condenser 26 obviously may be made to change its value as smoothly as desired, by making the steps smaller, or by any other well-known expedient.

The adjustment of circuit 25 to give the substantially flat or distortionless amplifier characteristic, may be utilized for track speeds which are high enough to give satisfactory reproduction of the higher frequency waves, for example, for the range of track speeds within the outer zone T of disk 10, Fig. 1. As the recording head 5 feeds toward the center of the disk, the speed progressively decreases through the zones T, U, V, W, X, cam 34 being so shaped as to progressively adjust condenser 26 and thereby adjust the transmission characteristic of amplifier 3, so that at any instant, the transmission characteristic is adapted for the particular speed zone within which the waves are being recorded, as indicated by the use of similar letters on the curves and zones.

The reactance of condenser 26 is so high at the lower end of the utilized frequency range that the condenser acts as an open circuit and has no substantial effect on the transmission level, whereas at the higher frequencies its reactance is so low that the condenser acts substantially as a short circuit across resistance 18. It is assumed for the purpose of illustration, that the speed in zone U has decreased so low as to cause an appreciable loss of the higher frequency components, if these components were all recorded in normal amplitude relation. When recording in the zone U, the condenser 26 is given such a value that at the predetermined point on the frequency scale where the higher frequency components begin to suffer attenuation of the kind indicated by the droop of the curves, Fig. 2, these components receive an extra amplification or gain which increases with increase of frequency, thus giving a predetermined distortion to the recording current by making the ratio of the am-

plitude of the higher to the lower frequency waves, greater than in the original waves.

In the successively lower speed zones V, W, X, the point at which compensation begins, successively shifts to lower frequencies, thus widening the frequency range or band within which the higher frequency components are given an increased level. The maximum gain is determined by the amplification obtainable when the negative feed back coupling is effectively short circuited by the low impedance or reactance of compensation circuit 25. The upper limit of gain is preferably fixed at a predetermined value to limit or prevent objectionable squeezing of the reproducing stylus by the higher frequency components, as mentioned above. This upper limit of gain is shown by the flat upper end of the curves in Fig. 3. The combination of negative feed back with the short circuiting effect of circuit 25, prevents the gain from exceeding the desired value, but permits of obtaining a gain for the higher frequency waves sufficiently above normal relatively to the gain for the lower frequency waves to insure of appreciable improvement in the reproduction of the waves.

The curves in Fig. 4 show the effect of varying the resistance in circuit 25. Curve V is the same as in Fig. 3 and represents the decibels gain when the capacity C of condenser 26 is used alone in circuit 25, with negligible or zero resistance. Curve C, R_1 , shows the gain when the value R_1 , of resistance 27 is appreciable, while the capacity C, of condenser 26 is the same as with curve V. Curve C, R_2 , shows the gain when the resistance 27 is increased in value from R_1 to R_2 , while capacity C stays the same as with curve V.

Increasing the resistance in this manner in circuit 25, widens the portion of the frequency scale within which there is increased gain, and shifts to lower frequencies the place where the gain curve starts rising, thus adjusting the gain to compensate conveniently for the attenuation of higher frequency components with decreasing track speeds. Increasing the resistance 27, also lowers the maximum gain at the upper end of each curve, thus making it possible conveniently to limit the amount of stylus squeeze. The described effect on curve V, of varying resistance 27 in series with one value of capacity 26, may be produced in a similar manner when using the other values of capacity corresponding with the other curves, Fig. 3.

When manual control of the transmission characteristic of amplifier 3 is desired, instead of automatic control by rack bar 28, the bar 28 may be removed or omitted, so that shafts 32 may be rotated manually, or if desired, plungers 37 may be omitted, so that shafts 42 may be rotated manually to independently control the adjustments of the impedance of compensation circuit 25.

The compensation circuit 25, Fig. 5, including variable inductance 46, variable condenser 26, and variable resistance 27 in series, may be substituted for the circuit 25 in Fig. 1 or 7, and is particularly useful in cases requiring special attention to prevent squeezing or blocking of the reproducing stylus. Shafts 42, shown in dotted lines in Fig. 5, control the impedance of circuit 25, use being made of mechanism of the kind described in connection with Fig. 1, so that adjustment of circuit 25 at each instant corresponds with the position of head 5 and the linear speed of the record track, a separate cam 34 being provided for each element 46, 26, 27.

Circuit 25, Fig. 5, is preferably tuned to have a resonance peak close to or slightly above the upper frequency limit of the utilized frequency range when the track speed is in the maximum speed range T. The ratio of the amplitude of the higher frequency components relatively to that of the lower frequency components is thus made higher than normal. The amplification of the higher frequency waves may then be progressively increased with decrease of track speed to compensate for the drooping of the high frequency ends of the curves, Fig. 2, until the higher frequency components tend to squeeze the space available as a path for the reproducing stylus, in the speed range V, for example. At this point there should begin an adjustment of the resonance frequency down the frequency scale under the control of cams 34, to minimize the stylus squeeze by gradually lowering the gain at the upper end of the frequency scale with decreasing track speeds, while components somewhat lower down the scale which have less tendency to produce stylus squeeze, are given a gradually increasing gain or are only slightly changed in amplitude by the cams 34. Adjustment of resistance 27 alone, raises or lowers the level of the resonance peak. The described operations may thus produce a greater than normal ratio of amplitudes of high to low frequency components within a first range of track speeds, may increase this ratio in a lower track speed range, and then may decrease this ratio within a still lower speed range, while maintaining the ratio above normal relatively to the waves from the original source throughout the recording operations, so that some compensation is still obtained for the drooping current at the upper end of the frequency scale at the lowest track speeds.

Fig. 7 shows a push-pull amplifier A₂, similar to the one tube amplifier A₂ of Fig. 1, with similar reference characters applied to similar elements. It will be noted that resistance 17 is common to input circuits 14, 14', and output circuits 19, 19', while the negative feed back coupling resistances 18, 18', individual to input circuits 14, 14', respectively, branch away from resistance 17 and have their terminals remote from resistance 17, linked by the compensation circuit 25.

Circuit 25 is controlled by shafts 42 as in Fig. 1. The push-pull form of circuit offers the usual advantages of push-pull operation over single tube operation. A further advantage is that the compensation circuit leads are symmetrical with respect to the mid-points of the amplifier. The operation of the Fig. 7 circuit will be clear in view of the description of Fig. 1 which operates in a similar fashion.

Fig. 8 shows a reproducing circuit, including the pick-up head 48 for reproducing waves recorded on the disk 10, and transmitting the waves through amplifiers A₁, A₂, A₃, to the loud speaker LS. Amplifier A₂ is of the negative feed back type, similar to that of Fig. 1 or Fig. 7, except that compensation circuit 25 includes the inductance coil 46 and the resistance 27, in this respect being similar to Fig. 5. Fig. 9 shows the decibels gain of amplifier A₂, Fig. 8, over the utilized frequency range. The impedance or inductive reactance of the coil 46 at the lowest used frequencies, is relatively low or negligible, and at the higher frequencies is so high as to act as an open circuit. The negative feed back at the lowest frequencies is thus reduced, but is unaffected at the higher frequencies. Consequently the amplification of the lower frequency waves is greater than that

of the higher frequency waves, thus compensating for reduced low frequency amplitudes in the recording current. Where no such compensation is desired for the low frequency currents, the resistance 27 may be adjusted so high that the gain is substantially constant throughout the utilized frequency scale.

Fig. 10 shows the microphone or other source of waves 1, transmitting current to the amplifiers 2 and 4 in cascade, coupled with the recording head 5. The compensation control circuit 50, shunting the line between amplifiers 2 and 4, includes the resonant circuit consisting of the variable inductance coil 51 in parallel with the variable condenser 52, in series with the variable resistance 53. By making circuit 51, 52 resonant at a frequency, preferably at or slightly above the highest frequency in the utilized range, and adjusting resistance 53, by shafts 42, as in Fig. 1, a maximum amount of current is shunted from the line at the lower frequencies, so that the amplified current transmitted to the head 5, slopes up to a maximum at the higher frequencies. At low track speeds, the maximum shunting is obtained by reducing resistance 53 to a minimum. The resulting drain of current from the line, reduces the level of all the components to such an extent that potentiometer 54 is provided in the line to restore the current level to its proper value, the potentiometer being automatically adjusted along with elements 51, 52, 53, by shafts 42 and the other mechanism described in connection with Fig. 1. Control of coil 51 and condenser 52, permits of varying to some extent the ratio of inductive to capacity reactance and the slope of the compensation curve, without changing the resonant frequency.

It is thus possible with the Fig. 10 circuit, to partially, although not completely obtain recording current characteristics similar to curves T, V, X, Fig. 6. When shock excitation difficulties are to be avoided, the type of circuit shown in Figs. 1 and 7 is to be preferred. It will be noted that the Fig. 10 circuit requires at least four control shafts 42 and corresponding associated mechanism, if each element 51, 52, 53, 54, is to be adjusted, as contrasted with only two control shafts 42 in Fig. 1.

While vacuum tube amplifiers have been disclosed in connection with the described circuits, it will be understood that linear amplifying devices of other types adapted to utilize negative feed back couplings, may be employed. It will also be understood that the wave transmission circuits, including the amplifiers and the controls therefor, may be applied to other uses than the recording and reproduction of waves. The recording head, while described as recording at progressively decreasing track speeds, may record at increasing track speeds, as when the head is fed radially outward from the center of the record.

The invention is applicable, not only to disk records, but to records of other types wherein the track speed varies or is so low as to interfere with suitable recording or reproduction of the higher frequencies or of components in some other part of the utilized frequency range. The cam control mechanism may utilize cams of shapes designed for other purposes than those specifically mentioned. For example, in the case of sound recording or sound reproduction, cams may be employed with such shapes of contours as to vary the quality of the sound recorded or reproduced along the track, for special sound ef-

fects or novel sound quality. These and various other applications of the features of the invention will be understood to come within the broader aspects of the invention as set forth in the accompanying claims.

We claim:

1. The method of recording sound waves or other waves in a record track at a relatively low, progressively decreasing speed along the track, which consists in recording said waves while subjecting them to a preliminary distortion, said distortion including the operation of progressively increasing the ratio of the amplitude of said waves within a higher frequency band to the amplitude of said waves in a lower frequency band until a predetermined increase in said ratio has been reached while the track speed decreases, and widening said higher frequency band without substantially exceeding said predetermined increase in ratio during said decrease of track speed.

2. The method of recording sound waves or other waves in a record track at a progressively changing speed along the track, said method including the operation of recording said waves while subjecting them to distortion, said distortion consisting of making the transmission level of certain of the higher frequency waves to be recorded greater than that of certain of the lower frequency waves to be recorded, progressively changing in one direction the level of certain of said higher frequency waves during a predetermined change of track speeds and progressively changing in the opposite direction the level of at least a part of said higher frequency waves during a further change of track speeds continued in the same direction beyond said predetermined change of track speeds.

3. The method of recording sound waves or other waves in a record track at different speeds along the track, which consists in recording said waves while subjecting the original waves to a preliminary distortion within a predetermined first range of track speeds, said distortion including the operation of making the ratio of the amplitude of certain of the higher frequency waves to the amplitude of certain of the lower frequency waves greater than in the original waves, and within a predetermined second range of track speeds below said first range, making said distortion less than in said first range but greater than in the original waves.

4. The method of transmitting waves to a recording head through a section of the wave path between the source of waves to be recorded and the recording head, while the speed of travel of the recording head along the record track progressively changes, said method consisting of transmitting waves of different frequency through said section with substantially no distortion within a predetermined higher range of track speeds, making the transmission level of waves in a band of higher frequency relative to waves of lower frequency greater than normal within a second range of track speeds lower than said first mentioned speed range, and in a third range of track speeds lower than said second speed range, widening said band and making the transmission level of waves in said band greater than in said first speed range, but preventing the transmission level of waves in said band from exceeding that in said second speed range.

5. In a system for recording sound in a record track at different speeds along the track, the

method of transmitting waves through a section of the path between the source of waves to be recorded and the record track, said method consisting in transmitting waves of different frequencies over said section without distortion while recording within a first range of track speeds, transmitting certain of the higher frequency waves over said section at more than normal level relative to certain of the lower frequency waves while recording within a second range of track speeds below said first range, and transmitting certain of the higher frequency waves over said section at more than normal level relatively to said low frequency waves but at a lower level than during said second range, while the track speed is within a third range lower than said second range.

6. In combination for recording waves along a record track at relatively low speed, a wave recording head, and an amplifier coupled with said recording head for supplying thereto the waves to be recorded, said amplifier having a negative feed back coupling having a characteristic which decreases the feed back for waves in the upper part of the utilized frequency range relatively to that for waves in the lower part of said range.

7. In combination for recording waves along a record track at relatively low speed, a wave recording head, and an amplifier coupled with said recording head for supplying thereto the waves to be recorded, said amplifier having a negative feed back coupling having a characteristic which decreases the feed back in the upper part of the utilized frequency range relatively to that of waves in the lower part of said range, said coupling including a resistance and an impedance in shunt with said resistance, said impedance including a capacity reactance element.

8. In combination, means for tracing a relatively low speed wave record track, a wave transmission circuit coupled with said tracing means, an amplifier in said circuit, said amplifier having a negative feed back coupling, said coupling including a resistance in series with the input circuit of said amplifier and an impedance in shunt with said resistance, said impedance having a frequency selective distortion characteristic within the utilized frequency range of said amplifier.

9. In combination, means for tracing a relatively low speed wave record track, a wave transmission circuit coupled with said tracing means, an amplifier in said circuit, said amplifier having a negative feed back coupling, said coupling including a resistance in series with the input circuit of said amplifier and an impedance in shunt with said resistance, said impedance including reactance of only one sign and having a frequency selective distortion characteristic within the utilized frequency range of said amplifier.

10. In combination, means for tracing a wave record track at relatively low speed, a wave transmission circuit for said wave tracing means, an amplifier in said circuit, said amplifier having a negative feed back coupling, said coupling having a frequency selective distortion characteristic within the utilized frequency range of said amplifier, and means for changing the distortion characteristic of said coupling in timed relation with changes of said track speed.

11. The method of recording sound waves or other waves in a record track at a relatively low, progressively changing speed along the track,

said method including subjecting the original waves to a distortion, said distortion including making the ratio of the amplitude of components of said waves in a higher frequency band to the amplitude of components of said waves in a lower frequency band greater than in said original waves, changing said ratio inversely to change of track speed while the track speed is above a diminished value at which said ratio reaches a predetermined high value, keeping said ratio from substantially exceeding said predetermined high value while the track speed is less than said diminished value, changing the width of said higher frequency band inversely to said change of track speed, and recording the resulting distorted waves.

12. The method of recording sound or other waves in a record track at a relatively low, pro-

gressively changing speed along the track, said method including subjecting the original waves to a distortion, said distortion including making the ratio of the amplitude of components of said waves in a higher frequency band to the amplitude of components of said waves in a lower frequency band greater than in said original waves, changing said ratio inversely to change of track speed while the track speed is above a diminished value at which said ratio reaches a predetermined high value, maintaining said ratio at substantially said predetermined value while the track speed is less than said diminished value, changing the width of said higher frequency band inversely to said change of track speed, and recording the resulting distorted waves.

JACKSON O. KLEBER.
LINCOLN THOMPSON.

CERTIFICATE OF CORRECTION.

Patent No. 2,239,042.

April 22, 1941.

JACKSON O. KLEBER, ET AL.

It is hereby certified that the name of the assignee in the above numbered patent was erroneously written and printed as "The Sound Scriber Corporation" whereas said name should have been written and printed as --The SoundScriber Corporation, of Stamford, Connecticut, a corporation of Connecticut--, as shown by the record of assignments in this office; and that the said Letters Patent should be read with this correction therein that the same may conform to the record of the case in the Patent Office.

Signed and sealed this 27th day of May, A. D. 1941.

Henry Van Arsdale,
Acting Commissioner of Patents.
